MOUNTING BAR FOR HANGERS

Robert L. Reese, Youngstown, Ohio

Application November 7, 1958, Serial No. 53,303

Term of patent 14 years

(Cl. D54—2)

Fig. 1 is a front perspective view of a mounting bar for hangers showing my new design; and

Fig. 2 is a rear perspective view thereof.

I claim:

The ornamental design for a mounting bar for hangers, as shown.
